Primary Examiner — Marianne Pandozzi*Assistant Examiner* — Jae Liang(74) *Attorney, Agent, or Firm* — Jeffrey Schox; Thomas Gwinn**CLAIM**

I claim the ornamental design for a drinking glass, as shown and described.

DESCRIPTION

FIG. 1 is a top, right perspective view of a drinking glass showing my new design;

FIG. 2 is a bottom left perspective view thereof;

FIG. 3 is a top plan view thereof;

FIG. 4 is a right side elevational view thereof;

FIG. 5 is a bottom plan view thereof;

FIG. 6 is a cross section view showing a section taken along line 6-6 of FIG. 3; and,

FIG. 7 is a cross section view showing a section taken along line 7-7 of FIG. 3.
